(57) **CLAIM**

The ornamental design for a sock, as shown and described.

DESCRIPTION

FIG. 1 is a front, right side perspective view of a sock in accordance with my new design;

FIG. 2 is a front, right side perspective view of the sock in an in-use configuration, with the toes and lower leg of a user illustrated in broken lines;

FIG. 3 is a front elevational view of the sock;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines in the figures are for the purpose of showing environmental structure and form no part of the claimed design.
